UNITED STATES PATENT OFFICE.

ERNST TENSFELDT, OF CHARLOTTENBURG, NEAR BERLIN, GERMANY.

APPLIANCE FOR STORING TYPE BARS.

Application filed October 16, 1926, Serial No. 142,089, and in Germany October 17, 1925.

My invention relates to appliances for storing type bars and more particularly type bars which are not constituted by a unitary bar but are composed from single or "short" type.

It is an object of my invention to provide an appliance of the kind described in which the types are held reliably in their frames and the frames are so designed as to permit ready attaching of a card or the like for indicating the matter which is printed by the bar in the frame.

To this end, I equip each frame with a tubular type support. The type support is slotted longitudinally for the reception of the type shanks which are inserted in the slot so that their heads project from the support on the outside. The frame is provided with a check plate at one end by which the tubular support is closed. At the opposite end the support is open for the insertion of the types.

It is another object of my invention to provide a box or magazine in which the type frames are stored and which is provided with means for locating each frame in a definite position and for preventing the types from leaving the tubular support.

Types of the kind which are used in connection with my appliance are old in the art. Their shanks are conical and provided with two diametrically opposite grooves to facilitate securing of the types in the printing cylinder.

Heretofore the types constituting the bars were stored in cylindrical or polygonal tubular supports in which they were inserted by a longitudinal slot and held by a spring or a clamp on each end of the tube. In this construction it was difficult to ascertain immediately the matter to be printed and this is a particularly serious drawback in the case of ready matter, for instance addresses.

This drawback is overcome in my invention by combining the tubular support for the types with a holder for an index card on which the matter of the type bar may be printed or which may be provided with a number or other indication by means of which the matter of the bar may be ascertained from a schedule or the like. The holder is secured on one side of the tubular type support so that the frame tends to assume a definite position in the box or magazine in which it is stored. The means for preventing types from leaving the tubu-

lar support are eliminated in the frame except for the check plate at one end. The means for the same purpose at the other end of the support are carried on the box or magazine. Springs or clamps on the tubes themselves are dispensed with.

In the drawings affixed to this specification and forming part thereof an appliance embodying my invention is illustrated diagrammatically by way of example.

In the drawings

Fig. 1 is an elevation,

Fig. 2 is an end elevation, of a type frame.

Fig. 3 is a plan view,

Fig. 4 is a section on the line IV—IV in Fig. 3 illustrating a box or magazine having integral check plates for the open ends of the tubular supports,

Figs. 5 and 6 are similar illustrations of a box or magazine in which the checks are constituted by a bent strip of sheet metal inserted in the box.

Referring first to Figs. 1 and 2, *a* is the tubular type support which may be cylindrical as shown but may also be of polygonal or other cross section, and *b* is the card holder which is secured on one side of the tubular support *a* by soldering or any other suitable method. A longitudinal slot *c* is formed in the side of the tubular support which is opposite the holder *b*. At one end of the holder *b* a check plate *e* is formed by bending which closes the tubular support *a* at that end and at the same time serves as a base plate for the frame to stand on. The longitudinal edges of the holder *b* are rebent at *f* and serve for supporting an index card or the like *g* so that the matter of the type bar which is supported in the frame, may be identified at a glance.

The frames are stored in a box or magazine *h* which is rectangular in plan view with its edges bent upwards. Tongues *i* are punched from the bottom of the box substantially at its centre and serve for locating the frames. When the frames are in position in the box, their holders will tend to assume the inclined position indicated in Figs. 4 and 6 in which their cards are presented to a spectator viewing them from the front edge of the box. The check plates *e* of the frames abut against one of the side walls of the box and checks *k* are provided along the opposite side wall which form abutments for the holders *b*, the ends of the supports *a* which project beyond the holders *b* being in-

2
sserted between the check plates *k*. It will appear that when the frames are in this position the types *d* are retained in the slot *c* by the check plates *k*.

5 In the box illustrated in Figs. 3 and 4 the check plates *k* are formed by punching and bending upwards from the bottom of the box, similarly to the locating tongues *i*. In the box illustrated in Figs. 5 and 6 and 10 which is otherwise similar to the box described with reference to Figs. 3 and 4 and the corresponding parts of which have been marked with the same reference letters, the check plates *k* are constituted by a zigzag-shaped strip *k'* from sheet metal or the like, the ends of the tubular supports *a* being inserted in the depressions of the strip while its elevated portions serve for preventing the types from leaving the slots *c*.

20 Obviously the tongues *i* might be replaced by a similar strip, and the strip might be corrugated instead of being bent at right angles. Generally, I wish it to be understood that I am not limited to the exact details of 25 construction shown and described, for obvious modifications will occur to a person skilled in the art.

I claim:—

30 1. An appliance for storing type bars comprising a tubular support defining a longitudinal slot for inserting types, a card

holder secured to said tubular support, and a check plate closing one end of said tubular support.

2. An appliance for storing type bars 35 comprising a tubular support defining a longitudinal slot for inserting types, and a card holder secured to said tubular support, one end of said holder being bent over so as to constitute a check plate at one end of said 40 tubular support.

3. An appliance for storing type bars comprising a box, a frame comprising a tubular type support adapted to be inserted in 45 said box, and means adapted to be inserted in said box for retaining the types in said tubular support.

4. An appliance for storing type bars comprising a box, a frame comprising a tubular type support adapted to be inserted in said 50 box, and a zigzag shaped strip adapted to be inserted in said box for retaining the types in said tubular support.

5. An appliance for storing type bars comprising a box, a frame comprising a tubular type support adapted to be inserted in 55 said box, and a corrugated strip adapted to be inserted in said box for retaining the types in said tubular support.

In testimony whereof I affix my signature,

ERNST TENSFELDT.
